assignor to Ruben Rausing, Simonstorp, Blen-
tarp, Sweden

Application March 25, 1952, Serial No. 19,042

Term of patent 14 years

(Cl. D58—12)

To all whom it may concern:

Be it known that I, Harry Sigurd Valdemar Järund, a citizen of Sweden, residing at Lund, Sweden, have invented a new, original, and ornamental Design for Combined Tetrahedronal Shaped Packages and Container Therefor, of which the following is a specification, reference being had to the accompanying drawings, forming a part hereof, and wherein:

Fig. 1 is a perspective view of combined tetrahedronal shaped packages and container therefor, showing my new design;

Fig. 2 is a side elevation of the same, showing two of the tetrahedronal shaped packages partially removed from the container; and

Fig. 3 is a plan view of the same.

I claim:

The ornamental design for combined tetrahedronal shaped packages and container therefor, as shown.

HARRY SIGURD VALDEMAR JÄRUND.
